STUDENT DRAFTING TABLE

Harry N. Grow, Manitowoc, and Robert G. Rohde, Two Rivers, Wis., assignors to Hamilton Manufacturing Company, Two Rivers, Wis., a corporation of Wisconsin

Filed Jan. 22, 1962, Ser. No. 68,385

Term of patent 14 years

(Cl. D33—14)

FIG. 1 is a front perspective view of a drafting table embodying our new design;

FIG. 2 is a front elevational view, a portion of the top being broken away for convenience of illustration; and

FIG. 3 is a rear perspective view thereof.

The dominant features of our design reside in the portions shown in full lines.

The side of the drafting table not shown is the same in appearance as the side shown.

We claim:

The ornamental design for a student drafting table, substantially as shown and described.
